UNITED STATES PATENT OFFICE.

HENRY P. KRAFT, OF NEW YORK, N. Y., AND MAXIMILIAN CHARLES SCHWEINERT, OF WEST HOBOKEN, NEW JERSEY.

CAP FOR FOUNTAIN-SYRINGES OR THE LIKE.

1,146,430.

Specification of Letters Patent. Patented July 13, 1915.

Application filed February 19, 1909. Serial No. 478,884.

To all whom it may concern:

Be it known that we, HENRY P. KRAFT, residing in the borough of Brooklyn, county of Kings, city and State of New York, and 5 MAXIMILIAN CHARLES SCHWEINERT, residing in West Hoboken, in the county of Hudson and State of New Jersey, both citizens of the United States, have jointly invented certain new and useful Improvements 10 in Caps for Fountain-Syringes or the like, of which the following is a specification.

In a prior application filed by us on May 22, 1908, No. 434,352, we have described and 15 claimed a cap for fountain syringes, water bottles or the like, which is constructed of sheet metal in several parts. Such cap as exemplified in a fountain syringe nozzle comprises a body portion adapted to screw 20 into a water bottle or fountain syringe socket, a retaining device for the packing washer below such body portion comprising an annular plate fastened to the bottom of such body portion, an extension on 25 the top of the body portion adapted to form a handle or finger hold and a nipple to which the fountain syringe tube may be attached.

The present invention relates to a cap or 30 the like of this type constructed in one piece, the article being cast or molded of metal, rubber or the like. Certain other features of improvement will be hereinafter referred to.

35 Referring to the drawings illustrating one form of the invention, Figure 1 is a side elevation of a syringe nozzle made in accordance with the present invention. Fig. 2 is a top or plan view. Fig. 3 is a bottom view. 40 Fig. 4 is a longitudinal section taken on the line 4-4 in Fig. 2. Fig. 5 is a similar section taken on the line 5-5 in Fig. 2.

Referring to the drawings, let A indicate the cap as a whole which, as shown, is provided with a screw-threaded body portion B, and an upward extension C which is adapted to form a handle or finger hold by which the cap may be screwed into and out of its socket. When the invention is applied to a fountain syringe, the extension C is provided with a nozzle or nipple D designed to engage a suitable tube or the like. Each side of the extension C is constructed with a concave face E E', such 50 concave face being provided to secure a bet-

ter grip for the fingers upon the extension so that the operations of screwing and unscrewing may be facilitated.

The body portion B is provided at its lower end with a seating face F for the 60 gasket or packing washer G. This washer is held in place by an integral hollow extension H having a lower flange I, the packing washer being annular in form and embracing the extension H and the flange 65 I underlying the bottom of the washer and holding the same securely in place.

According to the present invention, the entire cap (with the exception of the packing washer) is made of one piece of metal 70 or other suitable material. As formerly constructed the body and its upward extension have been made of sheet metal joined together at a point corresponding to the flange J at the top K of the body. The extension 75 H and flange I have also been made in two parts. The assembling and uniting of the several parts of the stopper have heretofore taken considerable time which is not necessary in the present construction. Several 80 additional pieces are also saved. The cap of the present invention may be cast in one piece as illustrated, or it may be formed of rubber, either molded or blown into proper shape. The advantages of this construction 85 are apparent. The entire structure being made of one piece is not dependent upon any joints for its efficiency, is not liable to leakage and requires fewer operations to manufacture.

When the invention is applied to a stopper the nozzle D is, of course, omitted and the extension C closed at its upper end. By reason of the absence of joints such a stopper may be constructed with its bottom wall 95 open, for the reason that if water from the bottle should pass into the stopper it would be of no detriment since it could not leak out through the walls thereof. When the bottle is held upright to remove the stopper, 100 any water contained in the latter will, of course, run back into the bottle.

Although we have shown and described one form of our invention, we do not wish to be limited thereto as certain variations 105 may be made therein without departing from the invention. It will also be understood that, while we have described our invention with relation to a fountain syringe nozzle, it is applicable to other caps.

What we claim is:—

1. A cap for water-bottles, comprising a hollow exteriorly threaded body portion and a hollow flattened finger-piece above said body portion, and formed integrally therewith, said body portion having a flat bottom with a downwardly extending hollow neck having an integral outwardly extending flange at its lower end adapted to form, with the underside of the body portion, a retaining recess for a flat washer having a central perforation, said bottom being formed integrally with said body-portion and said neck being formed integrally with said bottom, and said hollow finger piece having an integrally formed hollow extension, constituting a nipple and adapted to receive the end of a hose or the like, said cap having an opening therethrough from its bottom to its top.
2. A cap for water bottles comprising a hollow exteriorly-threaded body portion,

said body portion having a flat bottom with a downwardly extending hollow neck having an integral outwardly extending flange at its lower end adapted to form, with the under side of the body portion, a retaining recess for a flat washer having a central perforation, said bottom being formed integral with the body portion, and said neck being formed integral with said bottom, and said cap having an integral upwardly extending nipple adapted to receive the end of a hose or the like, and said cap having an opening therethrough from its bottom to its top.

In witness whereof, we have hereunto signed our names in the presence of two subscribing witnesses.

HENRY P. KRAFT.

MAXIMILIAN CHARLES SCHWEINERT.
